No. 746,842.

PATENTED DEC. 15, 1903.

E. S. IRVIN & F. B. JACKSON.
NON-REFILLABLE BOTTLE.
APPLICATION FILED MAR. 13, 1903.

NO MODEL.

UNITED STATES PATENT OFFICE.

EDWIN S. IRVIN AND FRANKIE B. JACKSON, OF OAKLAND, CALIFORNIA,
ASSIGNORS TO RELIABLE NON-REFILLABLE BOTTLE COMPANY, OF SAN
FRANCISCO, CALIFORNIA, A CORPORATION OF CALIFORNIA.

NON-REFILLABLE BOTTLE.

SPECIFICATION forming part of Letters Patent No. 746,842, dated December 15, 1903.

Application filed March 13, 1903. Serial No. 147,565. (No model.)

To all whom it may concern:

Be it known that we, EDWIN S. IRVIN and FRANKIE B. JACKSON, citizens of the United States, residing at Oakland, in the county of Alameda and State of California, have invented certain new and useful Improvements in Non-Refillable Bottles, of which the following is a specification.

Our invention relates to non-refillable bottles, the object of our invention being to provide a device for preventing bottles from being refilled after having been used which shall be cheap and simple in construction, enabling it to be put upon the market at a price which will insure its adoption.

Our invention therefore resides in the novel construction, combination, and arrangement of parts for the above ends hereinafter fully specified, and particularly pointed out in the claims.

In the accompanying drawings, Figure 1 is a vertical section of a neck of a bottle equipped with our improvement. Fig. 2 is a side view of the tube-sections which hold the valve-seats assembled in place. Fig. 3 is a plan view of the cap-plate. Figs. 4, 5, 6, and 7 are detail views of said sections detached from each other, Fig. 7 showing also the valve thereon. Fig. 8 is a perspective view of one of the valve-seats and valves detached; and Fig. 9 is a section of the neck of the bottle in a horizontal position, showing the action of the valves.

Referring to the drawings, 1 represents the bowl of the bottle, and 2 the neck thereof. The lower end of said neck is formed with an annular shoulder 3, upon which rests a cork sleeve 4, within which enters the contracted lower neck 5 of a cylindrical tube 6, within which all the tube-sections and valves are assembled, said tube being then inserted within the neck of the bottle. Within said tube are inserted short tube-sections 7 8 9 10, the square end of the lower tube 7 resting upon the shoulder 11 at the bottom of the outer tube formed by said contracted neck 5. Upon the oblique upper end of said section 7 rests the lowermost valve-seat. There are three such valve-seats and valves identical in shape and

construction, the valve-seat 12 being elliptical in form, as shown, and having hinged thereto, as shown at 13, an elliptical valve 14. Said valve-seat is merely laid upon the oblique upper edge of the section 7, and the oblique lower edge of the section 8 is then laid upon it. In like manner the other valve-seats are laid in place, the tube-sections following on in regular order, said tube-sections holding the valve-seats in place within the outer tube 6. When said four tube-sections and three valve-seats have been so placed in position within the tube 6 and said tube and cork sleeve have also been inserted in the neck of the bottle, there is next inserted therein a cap-plate 15, which is star-shaped in form, as shown in Fig. 3, having four wings 16 and corresponding openings therebetween, through which the liquid can escape in pouring out.

The neck of the bottle is formed with an annular groove 17, which is at a level just above the top of the tube 6 when the latter has been inserted in place, so that when the cap-plate is pushed down upon the uppermost tube-section 10 it comes to a level with said groove. Into said cap-plate are drilled holes 18, and in said holes are placed bolts 19, pressed outward by springs 20. When inserting the cap-plate in the neck of the bottle, said bolts are pressed inward until the plate comes opposite to the groove 17, when they automatically spring outward by the pressure of said springs 20 and lock the cap-plate in the bottle-neck opposite to said groove. Said cap-plate also prevents the tube-sections and valve-seats from turning with reference to each other, and this is of importance, because said valves are arranged around the neck of the bottle or cross-sectionally at angles of one hundred and twenty degrees from each other. The consequence is that however the bottle be turned about its axis when in a horizontal position there will always be at least one of said valves whose hinge is above the center of gravity of the valve, so that the valve will drop into position to close the neck of the bottle. On account of the elliptical shape of the valve-seats said seats cannot turn when properly

clamped between the tube-sections, and thus said valves always retain the same relative position.

While we have herein shown a single cap-
5 plate, we do not limit ourselves to such a construction, but may use several such de-
vices, if necessary, or may vary the charac-
ter thereof, the cap-plate itself forming no
part of our invention, which resides in the
10 construction and relative arrangement of the
valves.

We claim—

1. In a non-refillable bottle, the combina-
15 tion with the neck of the bottle, of a tube in-
serted within said neck, inner tube-sections,
the terminal sections having outer squared
ends and inner oblique ends, median sections
having oblique ends, elliptical valve-seats
20 between the adjacent ends of sections, valves
hinged thereon, cross-sectionally at wide an-
gles from each other and means for securing
said sections and outer tube against longi-
tudinal removal from the neck of the bottle,
25 substantially as described.
2. In a non-refillable bottle, the combina-
tion of tube-sections, the terminal sections
having squared outer ends and oblique inner

ends, the median sections having oblique ends in planes at an angle with each other, elliptical valve-seats between the ends, valves 30 hinged to said seats cross-sectionally at wide angles from each other, and means for se-
curing said sections in line in the neck of the bottle with the seats therebetween against longitudinal displacement, substantially as 35 described.

3. In a non-refillable bottle, the combina-
tion of tube-sections having oblique abutting
ends, valve-seats at said ends and valves
hinged to move to and from said seats, the 40 hinges of said valves being wholly within the
inner cylindrical surface of the tube-sections,
and means for securing said sections together
in line in the neck of the bottle against lon-
gitudinal displacement therefrom, substan- 45
tially as described.

In witness whereof we have hereunto set
our hands in the presence of two subscribing
witnesses.

EDWIN S. IRVIN.
FRANKIE B. JACKSON.
